(57) **CLAIM**

The ornamental design for a foregrip for a firearm, as shown and described.

DESCRIPTION

FIG. 1 is a front view of a foregrip for a firearm, showing my new design;

FIG. 2 is a left side thereof;

FIG. 3 is a rear view thereof;

FIG. 4 is a right side view thereof;

FIG. 5 is a top view thereof;

FIG. 6 is a bottom view thereof;

FIG. 7 is a top, front, left perspective view thereof;

FIG. 8 is a top, front right perspective view thereof;

FIG. 9 is a bottom, front left perspective view thereof;

FIG. 10 is a bottom, front right perspective view thereof, and,

FIG. 11 is an exploded top, front, left perspective view thereof, where the top cover is lifted away from the remainder of the foregrip for a firearm of my new design.

1 Claim, 11 Drawing Sheets
